UNITED STATES PATENT OFFICE.

JOSEPH DU FRANES, OF NORTH TOPEKA, KANSAS.

COMBINED TENONING AND MORTISING MACHINE.

SPECIFICATION forming part of Letters Patent No. 366,822, dated July 19, 1887.

Application filed October 2, 1886. Serial No. 215,152. (No model.)

To all whom it may concern:

Be it known that I, JOSEPH DU FRANES, of North Topeka, in the county of Shawnee and State of Kansas, have invented a new and Improved Combined Mortising and Tenoning Machine, of which the following is a full, clear, and exact description.

My invention relates to a foot-power mortising and tenoning machine; and the invention consists, principally, in a practicable combination of the two machines.

The invention also consists in the feed mechanism, and in the means for holding and placing the cutters.

15 The invention also consists of the construction, arrangement, and combination of parts, all as hereinafter described and claimed.

Reference is to be had to the accompanying drawings, forming a part of this specification, 20 in which similar letters of reference indicate corresponding parts in all the figures.

Figure 1 is a front elevation of my combined mortising and tenoning machine. Fig. 2 is a sectional elevation of the same, taken on 25 the line *x x* of Fig. 1. Fig. 3 is a detailed sectional plan view taken on the line *y y* of Fig. 2, and Fig. 4 shows one of the tenoning knives.

A represents the upright frame of the machine supported upon the base A' and legs 30 A'', and constructed to form the ways B B, in which the frame C is vertically reciprocated for causing the mortising-knife *a* and tenoning-knives *b b*, carried thereby, to perform their work. The mortising-knife *a* is not carried directly by the frame C, but is held in a 35 cylindrical stock, D, held in the sleeve D', made a part of the plate D'', which is attached to the upper end of the frame C by a bolt, D'', which passes through a slot in the plate D'', so 40 that the plate may be adjusted back and forth upon the frame C by the screw D', to change the position of the knife *a*, as the work may require. The stock D is adapted to be turned in the tube D' by the handle *d*, for turning the 45 knife *a* to cut both sides and ends of the mortise.

The knives *b b* are secured by cleats and screws, or other obvious means, to projections *c' c'* of the side pieces, *c c*, of the frame C, and 50 are each formed with a diagonal cutting-edge, *b*, as shown in Fig. 4, to cut and remove the

timber T upon both sides to form the tenon *t*. (Shown clearly in Fig. 3.) The frame C is vertically reciprocated, to cause the knives *b* and *a* to do their work, by means of the treadle 55 E, connected to the frame by the connecting-rod E' and the connected springs E'' and E''', the former connected to the frame C by the projection *c'*, the latter held stationary upon the studs *c' c'*, attached to the main frame A. 60

The timber T to be worked is supported upon a table, F, held to the front of the main frame A by the heavy bolt F', passed through the table and through the cleat F'' at the back of the frame A, so that by loosening the nut 65 upon this bolt the table may be raised or lowered according to the width of the timber to be worked.

G represents a holding and feed frame for holding and feeding the timber to the knives. 70 This is attached to the table F by a bolt, G', passed through the horizontal board G'', attached to the lower edge of the frame G, as shown clearly in Figs. 1 and 3. Within the frame G is held the sliding feed-plate G'', which 75 is provided with a bent arm, *g*, and clamp-screw *g'*, for clamping the piece of timber T to the front surface of the feed-plate G'', as shown clearly in Fig. 1. The plate G'' is adapted to be moved longitudinally in the frame G, for 80 feeding the timber to and from the knives, by the screw H, which works in a screw-threaded opening made in the outer bar, *g''*, of the frame G, and passes through a screw-threaded opening in a cleat, *h*, attached to the feed-plate, as 85 shown clearly in Fig. 3.

Having thus fully described my invention, what I claim as new, and desire to secure by Letters Patent, is—

The vertically-sliding frame C, carrying the 90 block D'', and screw D', for adjusting the block D'' horizontally, and the knife-stock D, held in the sleeve D' of the block D'', in combination with the table F, frame G, horizontal sliding plate G'', provided with the clamp *g* and screw *g'*, 95 and the tenoning-knives *b*, attached to opposite sides of the frame C, substantially as described.

JOSEPH DU FRANES.
